Inventor:

Richd K. Evans

UNITED STATES PATENT OFFICE.

RICHARD K. EVANS, OF WASHINGTON, DISTRICT OF COLUMBIA, ASSIGNOR
TO THE CABLE RAILWAY COMPANY, OF SAN FRANCISCO, CALIFORNIA.

GRIPPING DEVICE FOR CABLE-WAYS.

SPECIFICATION forming part of Letters Patent No. 295,915, dated April 1, 1884.

Application filed August 13, 1883. (No model.)

To all whom it may concern:

Be it known that I, RICHARD K. EVANS, of the city of Washington, and District of Columbia, have invented certain Improvements in Grips for Endless-Cable Ways; and I hereby declare the following to be a full, clear, and exact description thereof, reference being had to the accompanying drawings, making part of this specification, in which—

10 Figure 1 is a side view of a clamping-plate of the upper jaw of a grip. Fig. 2 is a perspective view of a shoe to go into one of the jaws of the grip. Fig. 3 is a vertical section view of the jaws of a grip with the improved plate and shoe combined. Fig. 4 is a side view of a grip-jaw having channels in its lower face, and the shoe with corresponding ribs on its upper surface, the clamping-plate being shown in dotted lines. Figs. 5 to 11, inclusive, show 15 modifications of my improvement.

20 In all gripping devices now constructed for endless-cable ways, and especially those endless-cable ways adapted for propelling street-railway cars, the shank of the grip is a broad 25 and comparatively thin bar or series of bars of steel, moving edgewise through the slot in the sunken tube in which the cable is located. This construction produces great strength in the gripper in resisting edgewise strains, and 30 as a consequence, when by any accident some obstacle suddenly arrests the travel of the grip-shank through the slot in the tube, great and exceedingly dangerous breakage has followed.

35 The object of my invention is to provide a means for obviating such accidents and relieve the gripper of the cable when great and unexpected resistances are met by the gripper-shank; and my invention consists in providing the gripper with a device which will, at a predetermined strain, automatically relieve the 40 gripper of the cable, as will be hereinafter more specifically set forth.

45 In order that those skilled in the art may make and use my invention, I will proceed to describe the manner in which I have carried it out.

In the said drawings, Figs. 1, 2, and 3 illustrate the most economical form of my releasing device. The shank of the gripper *a*, which is 50 usually made of steel, is provided with the steel shoe-holder *b*, and at its lower extremity, on

the inner side, is provided a series of angular grooves, *c*, to receive correspondingly-shaped ribs *c'* on the cast-iron shoe *d*. Bolted to the side of the shoe-holder is the angular clamping-plate *e*, provided with a series of angular grooves, *i*, to receive the correspondingly-shaped ribs *i' i'* on the cast-iron shoe *d*. The lower shoe, *m*, and its holder *n*, are made after the same manner with the upper shoe and holder, with the exception that their sides are vertical. The ribs and grooves are the same. The cast-iron shoes alone are in contact, under pressure, with the cable *E*. After it is determined what amount of edgewise breaking-strain the shank of the gripper will bear safely, the ribs on the cast-iron shoe are made of a proper size to shear off immediately before such a strain is reached by the pull of the cable, and thereby allow the cast-iron shoe or 70 shoes to strip out of the gripper and release its hold on the cable. As the size of the ribs *c* and *i'* on the cast-iron shoe need only be of such strength as to safely bear the pull necessary to transport a loaded street-car, and, as 75 the pulling-strain is very much less than the strain to endanger the breaking of the gripper, the ribs may be made to shear off anywhere intermediate of these two limits of strain. The shoes *d* should be cast in quantities, and be on hand ready to replace any that may be stripped from the holders, and those which are stripped can be removed at leisure from the tube where they fall, as they can in no way interrupt the 80 travel of the cable.

85 Fig. 4 illustrates a modification of my invention wherein the ribs are cast on the top of the upper cast-iron shoe and on the bottom of the lower shoe, the grooves being in the bottoms of the receiving-sockets of the shoe-holders.

90 Figs. 5, 6, and 7 illustrate a modification wherein the clamping-plates and lower shoe-holders are provided with rectangular extension-plates *p p'*, which sustain the ends of the shoes, made with smooth surfaces, the said plates being made to sustain a predetermined breaking-strain, and in breaking they allow the shoes to strip from their holders and release the cable.

95 Figs. 8 and 9 (Fig. 9 being a cross-section of Fig. 8 on line *x x*) illustrate a modification of my invention wherein recesses *r r* on the

backs of the cast-iron shoes fit over ribs *t*, projecting from a soft-metal section, *P*, cast into the shoe-holders. This is highly advantageous when it is desired to have light breaking-strain 5 relieve the gripper.

Figs. 10 to 14, inclusive, illustrate a modification of my invention wherein a bolt, *k*, having a predetermined resistance, passes through the ends of the shoe-holders and sustains the 10 shoe.

The size of the bolt may be varied indefinitely without altering the bearings or holes in the shoe-holders by turning down the bolt between the interior faces of the two shoe-hold-

ers. In this form the ends of the shoes may 15 be rounded; but it is not necessary.

Having thus described my invention, what I claim as new, and desire to secure by Letters Patent, is—

The combination of a grip for cable-ways, 20 a removable shoe or shoes, and intermediate fastening devices adapted to rupture at a predetermined strain, substantially as described.

RICHD. K. EVANS.
